UNITED STATES PATENT OFFICE

FRANK T. SPIKEMAN, OF AKRON, OHIO, ASSIGNOR TO THE OSBORN MANUFACTURING COMPANY, OF CLEVELAND, OHIO, A CORPORATION OF OHIO

SLICE BAR

Application filed November 5, 1930. Serial No. 493,534.

This invention relates to apparatus for conveying loose material and for dropping the same at the end of the conveying stage in situations where it is necessary that the discharge from the conveyor be uniform in quantity. The particular application of the device herein shown is in conjunction with an endless type of conveyor used for handling foundry sand, and the immediate purpose to be accomplished is to give a uniform feed of such sand into the boot of an elevator, into a screen, or apparatus of a generally similar nature. Such sand is usually moist enough to pack readily, which gives it a tendency to drop from the end of the conveyor in large soft lumps. Particularly when feeding to shaking screens, evening out the flow to avoid such lumps increases the screen capacity, the increase at times amounting to as much as fifty per cent of the screen capacity. This invention is for the purpose of giving uniform discharge of the sand by breaking the large soft lumps so that the conveyor discharges the sand in a fairly continuous, substantially uniform stream.

A secondary object of the invention is the provision of a device of the sort described which will be rugged and certain in operation, relatively inexpensive, and which will permit the passage of solid pieces which may be carried along with the sand, such as unbroken lumps of hard baked sand, gaggers, chaplets, and so on, inasmuch as it is no object of the present invention to provide for the breaking of lumps which are hard enough to require a crusher or for separation out of foreign elements.

Although I have illustrated in the accompanying drawings, and described below, mechanism which embodies a preferred form of my invention, it is to be understood that the invention is not limited to such mechanism, but that it may be embodied in other modes, all falling within the scope of the claims.

In the accompanying drawings Fig. 1 is a side elevation partly in section of the discharge end of the conveyor to which my invention has been applied; and Fig. 2 is a front view of the same.

My invention may be applied to any suitable type of continuous conveyor, such as a fabric belt, link belt, or similar type, wherein a substantially continuous pile of sand is moved forward and spilled at the end where the conveyor turns down for its reverse run. Such a conveyor is generally indicated by the reference character 1 in Fig. 1 and is shown as comprising bottom elements 2 travelling along tracks 3 upon wheels 4. Side walls such as 5 may be provided to prevent the sand or other material from spilling out at the side. At the upper end a bull wheel 6 reverses the direction of the conveyor as shown. The supporting frame 7 of the conveyor is extended upwardly as at 8 and forwardly as at 9 to receive a pair of arms 10 pivoted at 11. A broad flat U-shaped bar or blade having a horizontal portion 12 and legs 12' is suitably fastened between the forward ends of these arms in such manner that the portion 12, which in the present showing is horizontal, normally hangs with its forward edge 13 slightly spaced from the travelling surface of the conveyor 1. Suitable elements, counter weights 14 in the present embodiment, tend to hold the arms 10 in such a position that the bar 12, positioned across the conveyor and slightly above it about the point where the downward turn starts. The rear end of the arms 10 are stopped in their upward movement by a cross bar 15, thus limiting the approach of the edge 13 to the conveyor surface by allowing the blade 12 to rise if an obstacle passes under it.

A chute 16 of any desired size may be provided to deliver the sand according to circumstances.

The operation of this apparatus is as follows:

Sand will automatically be placed on the conveyor and carried up thereby in a long continuous pile as indicated by reference character 20, Fig. 1. Since the sand is sufficiently moist to pack, its natural tendency is to drop off the end of the conveyor in fairly large coherent lumps. Although these lumps will crumble on striking the chute 16, they cause uneven flow of sand along the chute and deliver it to the screen or other member fed

by 16 in successive piles rather than in a uniform stream. This is objectionable, as pointed out in the statement of invention.

By putting the blade 12 somewhat above the bottom of the conveyor but low enough down so that a considerable portion of the sand passes over it, as shown at 21, the lumps which tend to detach themselves from the stream of sand at the turn of the conveyor are broken up and fall in an outer almost continuous stream 22 of small lumps and the sand below the blade 12 is dropped in a thin stream indicated by the reference character 23, too thin for the coherent masses to be objectionably large. The upper part of the sand, 21, which is pushed over breaks off by itself and passes out and beyond the support 12 so that here again the lumps are small and closely spaced, the total result of both actions being that the sand falls almost in two continuous streams without any coherent masses in either too large to crumble and merge into a substantially uniform stream on the chute 16.

The use of the apparatus has shown that without the blade 12 the cohesion of the sand enables objectionably large masses to ride around the gradual turn at the end of the conveyor but only very small masses can be pushed past the discharge edge of the blade 12 without dropping off.

In the particular form of conveyor shown there are a series of shallow pockets formed by the shape of the bottom elements of the conveyor. Although these cause some slight irregularity of delivery which is not eliminated by the bar 12, the volume of material handled by the conveyor is such that the relatively small irregularity so caused is of no consequence.

In case hard unbroken baked lumps of sand are carried along, as when sand cores get into the mold sand, or as may happen when the mold sand contains clay and the part adjacent a heavy casting has become baked, or if the sand contains pieces of metal, the resistance simply serves to lift the bar 12 until the edge 13 is far enough away from the conveyor to allow foreign bodies to pass under. As soon as they have passed the counter weight 14 restores the bar to its normal position, and the stops 15 prevent it from approaching the conveyor nearer than the proper setting. As stated above, the function of the blade 12 is simply to prevent the discharge of large lumps due to the natural packing tendency of the moist sand.

I do not limit myself to the embodiment of the invention which is described above and illustrated in the drawings, but set forth the scope of my invention in the appended claims.

What I claim is—

1. A continuous conveyor, means for directing said conveyor downward at the discharge end, and a flat blade disposed across said conveyor at the discharge end, said blade

being substantially horizontal in the longitudinal direction of the conveyor and substantially tangent to the beginning of said downward curvature, and being positioned somewhat above the conveyor bottom but 70 within the path of the conveyor load.

2. In combination, an endless conveyor adapted to have loose material piled thereon, means for changing the direction of travel of said conveyor to discharge material therefrom, and a broad flat bar adjacent said conveyor in the path of part of said material at the point of change of direction adapted to support part of said material to be pushed over the rear edge of said bar by the on- 80 coming material.

3. In combination with a conveyor having an upwardly directed flight and a downwardly directed discharge end, a horizontal blade disposed across said conveyor at the 85 discharge end, said blade being mounted for a normal spaced position above said conveyor but in the path of the load carried thereby, means permitting increase of said space, and means tending to hold said blade 90 in normal position.

4. In combination with a continuous conveyor for loose material means for directing said conveyor on a downward path at the discharge end, a flat blade above the conveyor 95 bottom adjacent the beginning of said downward path but below the top of the average load, and yieldable means for maintaining said blade in operative position.

5. In combination with a series of conveyor 100 elements means for directing said conveyor elements on a downward curve at the discharge end, a horizontal transverse bar spaced from said conveyor near the beginning of said curve but in the path of the average 105 load and having its horizontal surface approximately tangent to said curve, and yieldable means for maintaining said bar in operative position.

6. In combination with a conveyor of the 110 continuous moving support type for loose material, said conveyor having a downward turn at the discharge end, a bar disposed edgewise thereto substantially tangent to the turn of the conveyor but above the conveyor 115 bottom a distance less than the usual height of material conveyed.

Signed by me this 31 day of October, 1930.

FRANK T. SPIKERMAN.
